CLAIM

The ornamental design for a drawer divider, as shown and described.

DESCRIPTION

FIG. 1 is a perspective view of a drawer divider according to a first embodiment showing our new design;

FIG. 2 is a top view thereof, with the bottom view being a mirror image thereof;

FIG. 3 is a front view thereof, with the rear view being a mirror image thereof;

FIG. 4 is a left side view thereof; with the right side view being a mirror image thereof;

FIG. 5 is a perspective view of a drawer divider according to a second embodiment showing our new design;

FIG. 6 is a cross section along lines 6-6 of FIG. 5;

FIG. 7 is another perspective view of the divider/shelf shown in FIG. 5, but with the divider/shelf in a different position; and,

FIG. 8 is a cross section taken along lines 8-8 of FIG. 7. The broken lines in the drawings are included for the purpose of illustrating environmental structure that form no part of the claimed design.

The drawer divider is shown with a symbolic break in its length, represented by wavy lines. The appearance of any portion of the article between the wavy lines forms no part of the claimed design.
